UNITED STATES PATENT OFFICE.

DANIEL P. FITZGERALD, OF NEWARK, NEW JERSEY.

MACHINE FOR MAKING LINK MESH.

1,092,251.

Specification of Letters Patent. Patented Apr. 7, 1914.

Application filed May 13, 1913. Serial No. 767,263.

To all whom it may concern:

Be it known that I, DANIEL P. FITZGERALD, a citizen of the United States, residing at Newark, in the county of Essex and State 5 of New Jersey, have invented certain new and useful Improvements in Machines for Making Link Mesh, of which the following is a specification.

My invention relates to a machine for 10 making link mesh. In such connection it has particular relation to the means for supporting the mesh during the forming operations.

Among the various styles and patterns of 15 the fabric, known among jewelers as link mesh, the efforts (so far as I am aware,) to secure the aid of machinery in its manufacture, have been confined or restricted to the one in which the intermeshed links are composed 20 of round rings, made from round wire, and it is this class of work that the present invention is intended to facilitate and improve.

In carrying out my invention, I make use 25 of a support or supports for the link mesh, one or both of which supports having upon its periphery, annular or spiral grooves, or is otherwise suitably formed, and which support is positively driven, to the end, that the 30 work in the process of formation is carried by the revolving support in one plane, and also held by its interior surface upon and elevated by said revolving support in a plane at right angles or transversely to the plane 35 of rotation of the support.

My invention is illustrated in the accompanying drawings in which—

Figure 1 is a top or plan view of such parts of a link mesh forming machine embodying 40 my invention, and Fig. 2 is a side elevation view of the same, partly sectional on line $x-x$ of Fig. 1.

In the drawings, 1 represents the table upon which are mounted the two shafts, 2 45 and 3, each of which carries a supporting roll, 4 and 5, having a ball or similar bearing 7. Each of said rolls 4 and 5 is firmly held upon, and moved by, its shaft 2 or 3 and both of them are adapted to be moved or 50 revolved in the same direction, at the same time, and to the same extent, by a ratchet and pawl feed 8, and 9 of well-known construction. These rolls are provided on their periphery with annular or spiral grooves 6, 55 as may be best adapted for the special work required, which work (the mesh fabric) 10

is placed or carried upon the periphery of the rolls. As these rolls 4 and 5 are intended to be used both as a support for the fabric, 10, while in process of making, and also for 60 the movement and advance of said fabric to the proper points or positions at which the additional links are to be added thereto, or connected therewith, and as a period of rest or stoppage is required at each operation of 65 the forming tools 12, I propose to use as a means for bringing about this irregular or intermittent movement of the rolls, any well known ratchet feed 9, which is adapted to make certain the proper and mutual action 70 and movement of said rolls.

The small rolls 11, each one of which may be mounted on a suitable shaft or spindle, have a plain surface of elastic or yielding material, such as felt, rubber or the like. 75 Being placed adjacent to the main rolls, 4 and 5, they are intended to be used in contact with the fabric 10, and to assist in holding the same in its proper place or position while being revolved or controlled by the 80 movement and action of the supporting rolls, and to prevent buckling of the fabric during the forming operations.

The tools for forming additional links for the fabric 10, are diagrammatically 85 illustrated at 12, and are of a construction well known in the art.

One important advantage of my invention is to be found in the fact, that by the use of the parallel rolls as a support, the 90 work can readily be manufactured in the form of an endless band or apron, the size of which can be determined by the size of the rolls 4 and 5 and the distance between the centers of said rolls. Again the space 95 between the supporting rolls 4 and 5 permits of the location of the forming tools in a position where their operation is readily observed, and said tools 12 are easily accessible for any desired change, replacement 100 or repair.

Having thus described the nature and object of my invention, what I claim as new, and desire to secure by Letters Patent, is:—

1. In a machine for making tubular fabric 105 of link mesh, a support for the work comprising essentially a roll inclosed by the fabric and having its periphery provided with a spiral groove to engage the inner wall of the fabric and support the same, and 110 means for positively rotating said roll to thereby advance the fabric in directions

parallel to and transversely of the plane of the axis of said roll.

2. In a machine for making tubular fabric of link mesh, a support for the work comprising a plurality of rolls inclosed by the fabric, in parallel relationship to each other and separated some distance from each other, the periphery of said rolls having a spiral groove to engage the inner wall 10 of the fabric, combined with means for positively driving said rolls intermittently to thereby advance the fabric in directions parallel to and transversely of the plane of the axis of said rolls.
- 15 3. In a machine for making tubular fabric of link mesh, a support for the fabric comprising essentially two rolls inclosed by the fabric, the periphery of the rolls engaging the inner wall of the fabric to support 20 the same and adapted to move said fabric intermittently at stated and regular periods, and means for positively rotating said rolls.
4. In a machine for making tubular fabric of link mesh, a support for the fabric 25 comprising essentially two parallel rolls in-

closed by the fabric, the periphery of the rolls engaging the inner wall of the fabric to support the same and adapted to move said fabric intermittently at stated and regular periods, link-forming mechanism arranged to operate in the space between said parallel rolls, and means for positively rotating said rolls.

5. In a machine for making tubular fabric of link mesh, a support for the fabric 35 comprising essentially two rolls inclosed by the fabric, the periphery of the rolls engaging the inner wall of the fabric to support the same and adapted to move said fabric intermittently at stated and regular periods, 40 a means for positively rotating said rolls, and an auxiliary roll arranged adjacent to each rotating roll and located outside the fabric to press said fabric upon the periphery of the rotating rolls.

DANIEL P. FITZGERALD.
